UNITED STATES PATENT OFFICE

ALFRED A. DENNIS, OF GRAND RAPIDS, MICHIGAN, ASSIGNOR TO VENEER MACHINERY COMPANY, OF GRAND RAPIDS, MICHIGAN

JOINTER

Application filed August 15, 1930. Serial No. 475,459.

The objects of this invention are:

- First, to provide improved means of feeding veneers, either singly or in piles, to a jointer.
- Second, to provide a structure in which a plurality of layers of veneer shall be clamped and effectively jointed at one operation and the process repeated without stopping and starting the entire machine.
- Third, to provide such a planer structure in which the feed and clamp for the veneer is readily adjustable to cut a definite width and provided with a scale.

Fourth, to provide such a structure in which the clamped veneers are effectively guided to the planer cutter head to form what is known as a "hollow" joint.

Fifth, to provide improved lubricating means for the conveyors for such a structure.

Sixth, to provide in such a structure a plurality of presser conveyors so associated with a bed conveyor that veneers can be effectively clamped and guided from one presser conveyor to the other.

Objects pertaining to details and economies of construction and operation will appear from the description to follow.

Preferred embodiments of the invention appear in the accompanying drawings, in which:

Fig. 1 is a front elevation of a jointer planer for veneer embodying the features of my invention.

Fig. 2 is a plan view of the structure as seen in Fig. 1.

Fig. 3 is an enlarged fragmentary detail elevation view of the clamp section of the feed means illustrated in Fig. 1 with parts broken away for clearness of illustration.

Fig. 4 is an enlarged detail sectional elevation on the plane of irregular line 4-4 of Figs. 1, 2 and 6, showing details of the adjusting guide means for the veneer feed bed, and of the guide and the yielding table.

Fig. 5 is an enlarged detail sectional elevation view on line 5-5 of Figs. 1, 2, 3 and 9, showing the details of the clamping cams and adjustment for operating the clamp for the veneer and the guide for the veneer and also the guide for the feed bed.

Fig. 6 is an enlarged detail broken plan view partially in section of the feed bed and guide means for the veneer and for the feed bed chain, taken on section line 6-6 of Fig. 4.

Fig. 7 is an enlarged detail transverse sectional elevation of the feed bed chain oiler device taken on line 7-7 of Figs. 1, 8 and 9.

Fig. 8 is a detail sectional elevation of said oiler device taken on line 8-8 of Fig. 7.

Fig. 9 is an elevation view of a modification of my machine in which a power driven, endless chain presser top feed is substituted for the presser rollers and belt structure of Fig. 1, the structures otherwise being the same.

The parts will be identified by their numerals of reference which are the same in all the views.

1 is the bed or body of my improved jointer machine. It is carried on pairs of legs 2. 3 is the dust exhaust pipe leading from the planer head. 4 is the planer head disposed on a vertical axis and driven by the motor 5 through belt 6 and pulley 7, see Figs. 1 and 9.

8 is an endless continuous feed bed and its conveyor chain disposed around feed rollers 81, 82. Roller 82 is adjustable for tension in any well-known way. 81 is the driving roll driven by motor 83 having clutch 84. The top presser feed rolls are actuated from this driving of the feed bed, as seen in Fig. 1.

On the top of the bed 1, at the feed end, is supported the yielding table 9 on a level a little above the feed bed. It is provided with inch scale marks at intervals thereon, see Figs. 2 and 6. A rigid table 10 is opposite the planer head 4 and extends the full length of the bed 1 with its top a little below the level of the feed bed 8. The table 9 is supported yieldingly on springs 91 so that it may be readily depressed to the exact level of the feed bed 8.

Toward the feeding end of the table I provide my improved veneer clamp feed means. This consists of a frame bar 11 which is supported on uprights 12 on the bed 1 which are each slotted at 121 to receive the attaching bolts 111 for securing the said frame bar 11 in place. A pair of adjusting screws 122

serve to control by fine adjustment the height of frame bar 11.

The clamp frame 13 adjusts up and down on the face of the frame bar 11. This is accomplished for clamping purposes by a pair of cams 14, see Figs. 1, 3 and 9, the cams being provided with lever arms 141 which are connected by the link 142 which is knurled to serve as a handle, so that the cams are operated simultaneously and quickly. These cams force the clamp frame 13 down. The clamp on its face is provided with a series of clamping rollers 15 which are journaled in suitable spring pressed blocks 151 which play up and down in guide slots 131 in the clamp bar 13. The rolls are held yieldingly downward by the springs 152 on shanks 153 which shanks reciprocate in suitable openings in the said clamp frame 13.

20 A presser top feed means cooperates with the feed bed opposite the cutter head and receives the clamped veneers. This presser feed conveyor comprises a frame bar 16. This is provided with a plurality of spring pressed rollers 17, comparable in all details with rolls 15, which cooperate with the said feed bed. Around these rollers 17 is disposed an endless belt 18 which insures the operation of the feed rolls after the engagement by them of the advancing end of the clamped veneers. The frame bar 16 is carried on uprights 12' exactly like uprights 12 and frame 16 is made adjustable by means identical with the means that adjust frame 30 bar 11.

A yielding guide 19, see Fig. 5, is pressed laterally by springs 191 and engages the links of the feed bed. Guide 192 on the opposite side is adjustable by set screws 193, 40 194, see Figs. 2 and 6. By adjusting this guide 192 so that it delivers the bed in a slightly curved path to the planer head, what is known as a "hollow" joint is produced. That is a joint in which the ends of the 45 veneer strips press slightly in advance of the center part, which insures a tight joint for the entire length of the veneer.

50 20 is a work guide that extends from the clamp section to the feed section terminating near the cutter-head. The work guide 20 is controlled by a pair of racks 201 connected thereto which are acted upon by a pair of segment gears or pinions 202, see dotted lines in Fig. 4. These are controlled by the lever 55 203 on rockshaft 204 on which the said segment gears 201, 202 are mounted. A scale 205 is provided for the adjustment of the said lever 203 which is clamped by set screw 206 to the slotted segment bar 207, see Fig. 6. The amount of cut can thus be very closely regulated.

The links of the feed bed conveyor are lubricated by providing an adjustable spring guide slide with felt pads saturated with lubricant, see Figs. 7 and 8. This lubricator

is a guide and consists of a back 21 with hinged side wings 22 held yieldingly in place by springs 23, see Fig. 7. Felts 24 and 25, 25 for carrying lubricant are carried by the back and sides. These are provided with 70 perforated faces 241, 251, 251 of sole leather to resist wear and permit through lubrication.

In operation with the machine running, a number of layers of veneer, see Figs. 3 and 5, are placed on the yielding table with their edges projecting over the feed bed against the veneer guide. The clamp 13 is forced down onto the same by the actuation of the cams 14. The veneers, directed by the guide 20 are then carried by the feed bed from under the clamp, owing to the revolving of the rollers 15 of the said clamp to the presser feed roller section, where as soon as the veneers are engaged they are advanced, because of the presence of the belt 18 around the said feed rollers. The feed bed being controlled by the guide 192, it carries the clamped and retained veneers past the cutterhead. Owing to the slight deflection of the feed bed, the planer forms what is known as a "hollow" joint.

When one edge of a bunch of veneers has been planed and jointed, the guide 20 is withdrawn. The veneers can then be 95 clamped separately in a pile together and adjusted in the machine according to the scale of the table 9 and the opposite edge uniformly planed and jointed. Thus identical veneer strips can be produced.

The structure of my machine can be varied by providing driven feed rollers and a chain feed for the final half of the machine as seen in Fig. 9. I show in Fig. 9 an endless feed carrier 24 driven by a pulley 25 which 105 pulls the carrier past feed rollers that are comparable to those appearing in the principal view, Figs. 1 and 3.

I desire to claim the invention broadly and also the two species that I have illustrated 110 specifically, as pointed out in the appended claims.

Having thus described my invention what I claim as new and desire to secure by Letters Patent is:

1. In a jointer, the combination of a suitable bed, a jointer planer head on a vertical axis, an endless chain feed bed with means for driving the same on the bed of the said planer in proximity to the cutter head, yielding guide means for said feed bed on the cutter head side thereof, adjustable guide means for deflecting the opposite side of said feed bed to slightly curve the path of travel of the said feed bed, an adjustable presser feed roller member above the said feed bed opposite the said cutter head with yielding presser rolls therein, an endless belt conveyor around the said presser rolls, a clamp presser feed conveyor means in advance of the said presser 125 130

feed roll comprising an adjustable clamp bar, 5
spring pressed rollers carried thereby, parallel cam means for actuating the said clamp bar for clamping veneers against the said feed bed, an adjustable guide opposite the said clamp and feed means extending into proximity to the said cutter head, and a yielding table top opposite the said clamp means with springs for supporting the same above 10
the level of the feed bed, the said table being provided with scale to set the work.

2. In a jointer, the combination of a suitable bed, a jointer planer head on a vertical axis, an endless chain feed bed with means 15
for driving the same on the bed of the said planer in proximity to the cutter head, yielding guide means for said feed bed on the cutter head side thereof, adjustable guide means for deflecting the opposite side of said 20
feed bed to slightly curve the path of travel of the said feed bed, a presser feed roller member above the said feed bed opposite the said cutter head with yielding presser rolls therein, a clamp presser feed conveyor means 25
in advance of the said presser feed roll comprising an adjustable clamp bar, spring pressed rollers carried thereby, parallel cam means for actuating the said clamp bar for clamping veneers against the said feed bed, an adjustable guide opposite the said clamp and feed means extending 30
into proximity to the said cutter head, and a yielding table top opposite the said clamp means with springs for supporting the same above the level of the feed bed.

3. In a jointer, the combination of a suitable bed, a jointer planer head on a vertical axis, an endless chain feed bed with means for driving the same on the bed of the said planer in proximity to the cutter head, yielding guide means for said feed bed on the cutter head side thereof, adjustable guide means for deflecting the opposite side of said feed bed to slightly curve the path of travel of the said feed bed, and a presser feed roller member above the said feed bed opposite the said cutter head with yielding presser rolls therein.

4. In a jointer, the combination of a suitable bed, a jointer planer head on a vertical axis, an endless chain feed bed with means for driving the same on the bed of the said planer in proximity to the cutter head, an adjustable presser feed roller member above the said feed bed opposite the said cutter head with yielding presser rolls therein, an endless belt conveyor around the said presser rolls, a clamp presser feed conveyor means in advance of the said presser feed roll comprising 55
an adjustable clamp bar, spring pressed rollers carried thereby, parallel cam means for actuating the said clamp bar for clamping veneers against the said feed bed, an adjustable guide opposite the said clamp and feed 60
means extending into proximity to the said

cutter head, and a yielding table top opposite the said clamp means with springs for supporting the same above the level of the feed bed, the said table being provided with scale to set the work.

5. In a jointer, the combination of a suitable bed, a jointer planer head on a vertical axis, an endless chain feed bed with means for driving the same on the bed of the said planer in proximity to the cutter head, a presser feed roller member above the said feed bed opposite the said cutter head with yielding presser rolls therein, a clamp presser feed conveyor means in advance of the said presser feed roll comprising an adjustable 70
clamp bar, spring pressed rollers carried thereby, parallel cam means for actuating the said clamp bar for clamping veneers against the said feed bed, an adjustable guide opposite the said clamp and feed means extending 75
into proximity to the said cutter head, and a yielding table top opposite the said clamp means with springs for supporting the same above the level of the feed bed.

6. In a jointer, the combination of a suitable bed, a jointer planer head on a vertical axis, an endless chain feed bed with means for driving the same on the bed of the said planer in proximity to the cutter head, a presser feed roller member above the said feed bed opposite the said cutter head with yielding presser rolls therein, a clamp presser feed conveyor means in advance of the said presser feed roll, an adjustable guide opposite 80
the said clamp and feed means extending 85
into proximity to the said cutter head, and a yielding table top opposite the said clamp means with springs for supporting the same above the level of the feed bed.

7. In a jointer, the combination of a suitable bed, a jointer planer head on a vertical axis, an endless chain feed bed with means for driving the same on the bed of the said planer in proximity to the cutter head, a presser feed roller member above the said feed bed opposite the said cutter head with yielding presser rolls therein, a clamp presser feed conveyor means in advance of the said presser feed roll, and a yielding table top opposite 90
the said clamp means with springs for supporting the same above the level of the feed bed.

8. In a jointer, the combination of a suitable bed, a jointer planer head on a vertical axis, an endless chain feed bed with means for driving the same on the bed of the said planer in proximity to the cutter head, a presser feed roller member above the said feed bed opposite the said cutter head with yielding presser rolls therein, a clamp presser feed conveyor means in advance of the said presser feed roll comprising an adjustable 105
clamp bar, spring pressed rollers, carried thereby, parallel cam means for actuating the said clamp bar for clamping veneers against 110
the said clamp and feed means extending 115
into proximity to the said cutter head, and a yielding table top opposite the said clamp means with springs for supporting the same above the level of the feed bed.

the said feed bed, an adjustable guide opposite the said clamp and feed means extending into proximity to the said cutter head, and a yielding table top opposite the said clamp means with springs for supporting the same above the level of the feed bed, the said table being provided with scale to set the work.

5. In a jointer, the combination of a suitable bed, a jointer planer head on a vertical axis, an endless chain feed bed with means for driving the same on the bed of the said planer in proximity to the cutter head, a presser feed roller member above the said feed bed opposite the said cutter head with yielding presser rolls therein, a clamp presser feed conveyor means in advance of the said presser feed roll, an adjustable guide opposite the said clamp and feed means extending into proximity to the said cutter head, and a yielding table top opposite the said clamp means with springs for supporting the same above the level of the feed bed, the said table being provided with scale to set the work.

10. In a jointer, the combination of a suitable bed, a jointer planer head on a vertical axis, an endless chain feed bed with means for driving the same on the bed of the said planer in proximity to the cutter head, a driven presser feed roller member above the said feed bed opposite the said cutter head with yielding presser rolls therein, a clamp presser feed conveyor means in advance of the said presser feed roll comprising an adjustable clamp bar, spring pressed rollers carried thereby, parallel cam means for actuating the said clamp bar for clamping veneers against the said feed bed, an adjustable guide opposite the said clamp and feed means extending into proximity to the said cutter head, and a yielding table top opposite the said clamp means with springs for supporting the same above the level of the feed bed.

15. In a jointer, the combination of a suitable bed, a jointer planer head on a vertical axis, an endless chain feed bed with means for driving the same on the bed of the said planer in proximity to the cutter head, a driven presser feed roller member above the said feed bed opposite the said cutter head with yielding presser rolls therein, a clamp presser feed conveyor means in advance of the said presser feed roll, an adjustable guide opposite the said clamp and feed means extending into proximity to the said cutter head, and a yielding table top opposite the said clamp means with springs for supporting the same above the level of the feed bed.

20. In witness whereof I have hereunto set my hand.

ALFRED A. DENNIS.
